UNITED STATES PATENT OFFICE

150,402

DESIGN FOR A FISHING ROD

Joseph Carlson, Grosse Pointe Farms, Mich., assignor, by court order, to Marie E. H. W. Carlson

Application September 9, 1946, Serial No. 133,185

Term of patent 14 years

(Cl. D31—4)

To all whom it may concern:

Be it known that I, Joseph Carlson, a citizen of the United States of America, residing at Grosse Pointe Farms, in the county of Wayne and State of Michigan, have invented a new, original, and ornamental Design for Fishing Rod, of which the following is a specification, reference being had to the accompanying drawing, forming a part thereof, wherein:

Figure 1 is a perspective view of a fishing rod embodying a rear grip showing my new design; and

Figure 2 is an end view taken on the line 2—2 of Figure 1.

The dominant feature of the design comprises the appearance of the rear grip, as illustrated in full lines.

I claim:

The ornamental design for a fishing rod, substantially as shown and described.

JOSEPH CARLSON.
